HERMAN C. BREHMER, OF PHILADELPHIA, PENNSYLVANIA, ASSIGNOR TO H. W. BUTTERWORTH & SONS COMPANY, OF PHILADELPHIA, PENNSYLVANIA, A CORPORATION OF PENNSYLVANIA.

GUIDE MECHANISM FOR CLOTH.

1,169,118.

Specification of Letters Patent. Patented Jan. 25, 1916.

Application filed June 12, 1914. Serial No. 844,635.

To all whom it may concern:

Be it known that I, HERMAN C. BREHMER, a citizen of the United States, and resident of Philadelphia, county of Philadelphia, 5 and State of Pennsylvania, have invented an Improvement in Guide Mechanism for Cloth, of which the following is a specification.

This invention relates to a guide mechanism for cloth and more particularly to a 10 means for centering the cloth being fed to a stentering machine or machine of like character.

The object of my invention is to provide 15 a motor device, controlled by a suitable pressure fluid, for operation with a trip mechanism adapted to maintain the width of the cloth within predetermined limits, all parts of said automatic mechanism being 20 constructed for sensitive and delicate action and capable of responding substantially instantly to abnormal conditions.

It has for a further object to provide a 25 motor wherein a movable part thereof is accurately and positively guided while the bearing of said movable part is so constructed that adjustments of other adjuncts of the motor have no effect thereupon.

My invention also comprehends details of 30 construction which, together with the features above specified, will be better understood by reference to the accompanying drawings, in which:—

Figure 1 represents a side elevation of a 35 guide and tension device embodying my invention; Fig. 2 represents a rear elevation of the same; Fig. 3 represents an end elevation of a stentering machine or machine of like character showing the guide and tension 40 devices in operative position; Fig. 4 represents a vertical section of the valve mechanism; Fig. 5 represents a section on line 45 5—5 of Fig. 4; Fig. 6 represents a plan of one of the bearing members for the valve stem.

1 designates a bracket provided with a suitable flanged part 2 by which it 50 may be removably secured by suitable fastening devices to the main frame of a stentering machine or machine of like character, or as shown in Fig. 3 may be connected to a rider or traveler 3 guided upon transverse rods 4 of the machine, and operated by the transverse feed screws 5 as will be under-

stood. There are ordinarily two brackets 55 at the ends of the machine, spaced apart a distance corresponding substantially to the width of the material being fed through the machine and the location of these brackets with respect to the said material will be 60 more fully disclosed in connection with the description of the guiding adjuncts carried by the aforesaid brackets. The bracket 1, in the present instance, carries a metal guide roll 6 rotatably mounted upon the fixed 65 spindle 7 and adjacent thereto is a movable spindle 8 carrying a second guide roll 9 preferably of rubber and arranged in opposed relation to the roll 6. The spindle 8 is journaled in a bell crank frame or yoke 70 10 of which one pair of the ends are connected by a tubular member 11 journaled upon the rod 12 which is fixed to the bracket 1. The opposite ends of the yoke 10 are joined by a transverse bar 13 having a 75 flanged portion 14 to form a bearing surface for contact with certain adjuncts of the operating mechanism. 15 designates suitable guide plates fixed to the bracket 1 in any desired manner and suitably located with respect to the rolls 6 and 9 80 in order to properly guide the material between the two rolls and also prevent the same from becoming entangled with the operating mechanism. It will, of course, be 85 understood that while I have described the rolls 6 and 9 as respectively of metal and rubber, I do not wish to be limited to these materials, as any suitable material may be used which is capable of properly gripping 90 and guiding the material to the machine. The two guide rolls 6 and 9 are arranged in substantially the same horizontal plane, whereas the guide plates 15 are arranged in a vertical plane, the fabric passing upward 95 between the said guide rolls 6 and 9.

16 designates a post preferably of angular form and having its base portion 17 mounted for adjustment upon the bracket 1 by means of the slot 18 and bolt 19. The outer or free 100 end of the post 16 is suitably apertured to receive the tubular extension 20 of a cylinder 21, the said extension projecting through the post 16 and being screw-threaded to receive the nut 22 by which the parts are 105 secured in assembled condition.

One end of the cylinder 21 is closed and provided with exhaust ports 23, while the

opposite open end has screw threaded engagement with a casing 24, within which is located the valve mechanism for controlling the operation of the parts contained within the cylinder 21. These parts comprise a piston 25 mounted for free reciprocatory movement within the cylinder and carrying a plunger 26 at one side which passes through and projects from the extension 20 for a purpose to be later described. The opposite side of the piston 25 is provided with a stem 27 journaled in an apertured disk or spider 28 by which the said piston is accurately centered so that it may reciprocate properly without binding or becoming distorted in use.

29 designates a spring encircling the plunger 26 and held between the piston 25 and the extension 20 so that its tendency is to return the piston 25 to normal position after the motive fluid has actuated the said piston.

In connection with the member 28 it will be noted that the outer ends of the radial arms thereof are circumferentially milled or machined as shown at 30, whereby one portion of the bearing member accurately fits the interior of the cylinder 21, while the remaining portion 30 seats between the shoulder 31 of the cylinder 21 and the threaded part 32 of the casing 24. It will further be seen that the part 30 has a thickness preferably less than the space in which it is seated in order to provide a slight clearance when the casing 24 has been properly assembled on the cylinder 31. This clearance prevents the spider 28 from being clamped in a fixed manner between the two parts and thus effectually eliminates twisting or buckling which would impair the proper movement of the piston 25.

33 designates the body portion of a valve member having oppositely disposed stems 34 and 35, the former passing through the closure cap 36 at one side of the casing, while the latter projects through the opposite side and is held by a screw 37 and washer 38 or like fastening means, though it will be noted that this connection is not such as to prevent free movement of the body portion within the casing 24.

The body part 33 is suitably bored to form intersecting channels 39 and 40, the former having communication with a port 41, which in certain positions of the valve body comes into alignment with the inlet conduit 42 for compressed air or other motive fluid. 43 designates the valve plug having a portion of its length of tubular form and seating within the bore 40. This plug, as here shown, is provided with a pair of ports 44 adapted to align at certain times with similar ports 45 provided in the wall of the casing 24 and communicating with the interior of the cylinder 21. When the two sets of

ports 44 and 45 are in alignment, the motive fluid has free passage into the cylinder 21 and to one side of the piston 25, as will be understood.

46 designates an exhaust port or channel 70 cut in the outer face of the valve piece adjacent the ports 44 and preferably extending from one side of the plug to the other so that when it in turn is in alignment with the ports 45, the pressure in the end of the cylinder 21 will be relieved and the motive fluid exhausted by way of the port 46 into the interior of the casing and from which it has free access to the outside of the casing by way of the opening 47 or the like. This 80 opening 47 permits access to the valve body, and it will be noted that one end of the port 40 is closed by a screw 48 so that upon its removal a suitable implement or tool may be inserted to adjust the valve piece 43 for 85 wear. The valve piece is ordinarily fixed in adjusted position by a set screw 49 in alignment with which is an opening 50 in the casing so that the screw may be readily manipulated. The screw 51 which is threaded 90 through the casing 44 serves as a stop to limit the throw of the valve body.

52 designates a rod adjustably mounted on the projecting end of the valve stem 34 and having one end threaded to receive a counter-weight 53 while intermediate its length there is a trip arm 54 which extends into the path of movement of the trip finger 55. This latter element is preferably pivoted to the post 16 and has its opposite end extended through one of the guard plates 15, where it assumes a position adjacent the path of movement of the material. The counter-weight 53 is normally adjusted so that the valve body 33 is positioned with the ports 44 in register with the ports 45, and since at this time the inlet port 41 is in alignment with the channel 42 the motive fluid has a free passage into the cylinder 21 and therefore maintains the plunger 26 outwardly 110 pressed. 56 designates a bell crank lever pivoted at 57 to the post 16 and provided with a lug or contact member 58 which is arranged in close proximity to the flanged contact surface of the yoke frame.

The operation of the device is as follows:— Before taking up the description of the operation of the machine and details, it should be borne in mind that the mechanism of my present invention is adapted for use in connection with the guiding and positioning of cloth which is being fed to a suitable machine, such machine being in the present instance a stentering machine for guiding and feeding cotton, woolen, linen, silk and other fabrics, though its use is not limited in this particular as it is readily applicable to all machines where a continuous run of cloth is required.

By reference to Fig. 3 the guide mecha- 130

nism embodied in my invention will be seen in its operative position at the end of the machine, and it will be noted that the guide rolls 6 and 9 are inclined with respect to the horizontal plane of the machine so that as the cloth is fed between the pairs of rolls it will receive an initial stretching preparatory to being delivered to the feeding rolls. While the slight incline is given to the axis 5 of the rolls to produce the stretching effect on the fabric, the relative arrangement of the two rolls 6 and 9 is in substantially a horizontal plane as the fabric passes between them in a vertical direction. In adjusting 10 the frames for the guide rolls, reference is had to the location of the trip fingers 55, since these oppositely disposed fingers should be spaced apart a distance substantially equal to the normal stretched width 15 of the cloth so that any further widening or stretching will cause the selvage of the material to strike one or the other of the fingers and thus automatically bring the valve mechanism into operation. Under normal 20 conditions the counterweight 53 holds the valve stem 34 in such a position as to admit pressure fluid to one side of the piston 25, thus forcing the plunger 26 outwardly 25 against the lever 56 and causing the latter to press against the yoke bar 13 while the roll 9 is thereby pressed against the cloth passing under the roll 6. When the cloth exceeds the desired width, or irregularities 30 in the selvage cause the fabric to strike the trip finger or trip fingers 55, the trip arm 35 54 is shifted to raise the rod 52 against the weight 53 and thus swing the valve piece 43 into exhaust position, that is, with the channel 46 in register with the ports 45. In 40 consequence the pressure within the cylinders 21 is relieved and the spring 29 draws the plunger 26 inwardly, whereupon the yoke member 10 carrying the roller 9 moves by gravity away from the roll 6 and relieves 45 the cloth. As soon as the cloth returns to its normal width and out of contact with the trip fingers, the valve mechanism automatically acts to admit pressure fluid into the cylinder and again bring the two rollers into 50 engagement with the cloth.

In connection with the adjustment of the bracket 1 relative to the machine frame or to the cloth being fed to the machine, it will be noted that the flanged part 2 is substantially pivotally mounted upon its supporting part so that the bracket may be turned to the required angle. Furthermore the relation between the supporting post 16 and the guide rolls is such that when the bracket is 55 positioned so that the plunger 26 of the motor is vertical, the rolls will be properly inclined to effect the necessary stretching of the cloth. The normal position of the motor is a vertical one and for efficient operation of the device the bracket should be 60

adjusted with great accuracy so that the reciprocating parts of the motor operate in a vertical manner. The importance of this arrangement will be apparent when it is understood that under operating conditions the 70 motor is continually reciprocating, or vibrating to be more exact, and the tendency to wear on one side or the other would be very great if the plunger 26 were in a position other than the vertical. As a further 75 safeguard for accurate operation of the cylinder 25 the spider bearing member 28 is provided and that portion of this member which fits within the cylinder 21 is just as accurately fitted as the piston itself, and thereby maintains the free end of the piston 80 centered at all times.

Another important feature of the device resides in mounting the motor supporting post in an adjustable manner upon the 85 bracket 1 since this construction affords a means for varying the throw or movement of the cloth gripping roll 9.

It will now be apparent that I have devised a novel and useful construction which 90 embodies the features of advantage enumerated as desirable, and while I have in the present instance shown and described the preferred embodiment thereof which has been found in practice to give satisfactory 95 and reliable results, it is to be understood that I do not restrict myself to the details, as the same are susceptible of modification in various particulars without departing from the spirit or scope of the invention. 100

Having thus described my invention, what I claim as new and desire to protect by Letters Patent is:—

1. In a device of the character stated, the combination of a suitable frame, a pair of 105 rolls rotatably mounted thereon in a substantially horizontal plane and relatively movable to and from each other, a vertically arranged cylinder and reciprocable piston therein supported by said frame, an operating lever positioned so as to be actuated by movement of said piston and adapted to transmit movement of said piston to one of said rolls in a direction at an angle to the direction of movement of the piston to vary 110 the distance between said rolls, means to shift the fulcrum of said lever relatively to the rolls to regulate the extent of relative movement between the rolls, a trip finger located adjacent to the rolls and in the path 115 of movement of the material being guided, and means controlled by the movement of said finger to actuate said piston.

2. In a device of the character stated, the combination of a suitable frame, a pair of 120 rolls rotatably mounted thereon and relatively movable to and from each other in a substantially horizontal plane, a vertically arranged cylinder and reciprocable piston 125 therein supported by said frame, an operating 130

- ing lever positioned so as to be actuated by a vertical movement of said piston and adapted to transmit movement of said piston to one of said rolls in a horizontal direction to vary the distance between said rolls, a pivoted trip finger located adjacent to the rolls and in the path of movement of the material being guided thereby, a valve device for controlling the pressure to and from 5 the cylinder and piston provided with a counterweighted arm in which the counterweight is located substantially in a horizon-

tal plane with the valve device whereby it is operated by gravity in one direction, said trip finger having a movable connection with 15 the counterweighted arm for operating the latter against the gravity action of the weight.

In testimony of which invention, I hereunto set my hand.

HERMAN C. BREHMER.
